PAPER WAXING MACHINE

John Bennett, Passaic, N. J.

Application January 24, 1940, Serial No. 315,411

3 Claims.

(Cl. 91—55)

My invention relates to new and useful improvements in a method of an apparatus for applying wax to paper.

An important object of my invention is the provision of an apparatus for waxing paper that provides means for regulating the thickness of the coating of wax to be applied to the paper.

Another object of my invention is the provision of an apparatus of the above-mentioned character that is adapted to direct a web of paper through a waxing vat and to thereafter pass the waxed paper through a cooling unit in a manner to harden the wax on the paper.

Still another object of my invention is the provision of an apparatus of the above-mentioned character that is constructed in a manner whereby very little of the web of paper will be unsupported during or between any of the waxing operations, thus permitting the paper to travel at a relatively high rate of speed.

Yet another object of my invention is the provision of an apparatus of the above-mentioned character that is simple in construction and that is uniquely assembled to promote a rapid and efficient waxing of the paper.

Other objects and advantages of my invention will be apparent during the course of the following description.

In the drawing, forming a part of this specification, and wherein like numerals are employed to designate like parts throughout the same,

Figure 1 is a side elevation, showing parts in section, of a device embodying my invention.

Figure 2 is a top plan view, showing parts broken away, of my device.

Figure 3 is a vertical sectional view taken on the line 3—3 of Figure 1.

Figure 4 is a vertical sectional view taken on the line 4—4 of Figure 1.

Figure 5 is a fragmentary vertical sectional view taken on the line 5—5 of Figure 2, and

Figure 6 is a vertical sectional view taken on the line 6—6 of Figure 5.

In the accompanying drawing, wherein for the purpose of illustration, is shown a preferred embodiment of my invention, the numeral 10 designates a supporting framework including upright members 11 arranged in a rectangular formation, which uprights are connected by spaced parallel longitudinally extending beams 12 and transversely extending beams 13. The web of paper 14 is taken from the supply roll 15 in the unwaxed state, passed successively through the waxing vat 16 and and cooling unit 17 and thereafter wound upon the winding roll

18. The supply and winding rolls 15 and 18 are provided with axles 19 and 20 which extend in bridging relation to the longitudinal beams 12 at opposite ends of the supporting framework, which axles are supported thereon by the journals 21 and 22.

The waxing vat 16 comprises a box-like receptacle 23 having an open top and adapted to receive a supply of heated wax 24 through the supply pipe 25. A discharge pipe 26 communicates with the receptacle adjacent the top thereof through the opening 27 in a manner to accurately regulate and control the quantity of wax within the receptacle. The wax which overflows through the opening 27 may be conveyed to a central container where it will again be introduced into the receptacle 23 through the pipe 25. A steam coil 28 is disposed within the receptacle adjacent the bottom thereof and includes an entrance pipe 29 and discharge pipe 30. The pipes 29 and 30 may be connected to any suitable steam line in a manner whereby live steam will be continuously caused to flow through the coil 28 to heat the wax 24 within the vat. The end 31 of the receptacle is provided at its opposite sides with upstanding lugs 32 and the idler roller 33 is journaled therebetween in a manner to support the web of paper 14.

The web of paper extends from the idler roller 33 below the idler roller 34 carried by the arms 35 of the bellcrank levers 36. The arms 37 of the bellcrank levers are bridged by a rod 38 the opposite ends of which are screw-threaded and extend through the arcuate slots 39 in the flanges 40 extending from the sides of the receptacle 23. Nuts 41 are screw-threadedly received by the extending ends of the rod 38 in a manner whereby the bellcrank levers may be pivoted to position the idler roller 34 a desired distance below the surface of the wax within the receptacle. Pivotal movement of the levers will cause the ends of the rod 38 to traverse the slots 39 and, upon tightening of the nuts 41, the levers will be securely held to position the idler roller at the desired depth.

The supporting bracket 42 bridges the receptacle 23 and with the cross member 43 disposed a substantial distance thereabove. The vertically disposed legs 44 of the bracket extend downwardly at opposite sides of the tank and are formed with spaced inturned flanges 45 which define guideways for the vertically slidable U-shaped bracket 46. A rubber roller 47 is journaled between the depending arms of the sliding bracket 46 and the opposite ends of the roller shaft ex-

tend beyond the legs of the supporting bracket 42 through the elongated slots 48 to receive the circular gears 49. The hand-screw 50 is screw-threadedly received by the opening 51 in the cross member of the supporting bracket and the free end thereof is rotatably connected to the U-shaped sliding bracket 46, whereby rotation thereof will effect raising or lowering of the roller 41. The metal roller 52 is journaled within the receptacle 23 between the opposite sides thereof and below the rubber roller 41. The extending ends of the roller shaft extend beyond the legs of the supporting bracket 42 and carry circular gears 53 in meshed relation with the circular gears 49.

The web of paper extends from the idler roller 34 between the rollers 41 and 52 and the hand-screw 50 may be actuated to move the rubber roller 41 into pressed engagement with the paper and in a manner to hold the paper in pressed engagement with the lower metal roller 52. Passage of the paper between the rollers will remove the surplus wax therefrom, which wax will return to the receptacle 23.

It is obvious that very little vertical adjustment between the rollers 41 and 52 will be necessary during the operation of the apparatus, and such adjustment as will be necessary will be relatively slight. Under no circumstance will it be necessary to move the rubber roller sufficiently to disengage the circular gears 49 and 53.

The cooling unit 17 includes an idler roller 54, which roller is of tubular formation, the ends of the tube being closed and having longitudinally extending shanks 55 supported on the beams 12 of the supporting framework by the journals 56. A liquid supply conduit 57 communicates with one end of the roller through the stuffing box 58, and the discharge conduit 59 communicates with the opposite end of the roller through the stuffing box 60, whereby a suitable cooling solution 61 may be continuously passed through the roller.

The cooling unit 17 also includes an elongated box-like receptacle 62 the bottom end and side walls of which are insulated, as at 63. The receptacle is longitudinally inclined from the horizontal and with the end 67 thereof, nearest the waxing vat 16, being disposed substantially lower than the end 68 remote therefrom. The metal plate 64 covers the open top side of the receptacle and is adapted to hold a liquid refrigerant therein. A blower 80 is supported above the plate 64 and the funnel-shaped hood 81 extends therefrom and with the peripheral edge thereof in slightly spaced relation with the plate, whereby the blast of air from the blower will be directed against the upper surface of the paper in a manner to hold the same in appressed relation with the plate.

An inlet conduit 65 extends from the pump 66 and communicates with the receptacle adjacent the top plate 64 at the highest end thereof. The inlet pipe 57 extending from the idler roller 54, connects with the pipe 65, as illustrated in Figure 2, whereby cooling solutions from the pump may be forced simultaneously through the roller and receptacle. The supply pipe 69 extends from a cooling solution supply tank (not shown) of brine, or the like, to the pump, and the pipe 59, discharging from the cooling roller 54, has the discharge pipe 70 leading from the receptacle 62 connected thereto. The pipe 59 also communicates with the central cooling solution supply

tank, whereby a constant circulation of the solution by the pump 66 may be effected.

The brackets 71 are supported by the longitudinal beams 12 and maintain the transverse roller 72 slightly spaced from the end 68 of the receptacle 62. The periphery of the roller 72 is formed with a plurality of vacuum cups 79 which grip the bottom surface of the web of paper and pull the same across the plate 64. The roller shaft 73 is journaled in the supports 71 and the opposite ends 74 thereof carry the pulleys 75. Endless belts 76 connect the pulleys 75 with the pulleys 77 carried by the drive shaft of the motor 78. The shaft of the roller 72 is provided with a pulley 82 and the blower shaft 83 is provided with a pulley 84 whereby the endless belt 85, connecting the pulleys 82 and 84, may impart rotation to the blower. The opposite ends of the shaft of the lower roller 52, operating in the waxing vat 16, are provided with pulleys 86, and the endless belts 87 are trained thereabout and about the pulleys 88 carried at the opposite ends of the shaft of the roller 72. The endless belt 89 connects the pulley 90 of the motor shaft and the pulley 91 of the pump, whereby operation of the motor will impart rotation to the pump to effect the circulation of the cooling solution through the cooling unit.

The web of paper 14 extends from the roller 12 below the idler roller 92, journaled between the longitudinal beams 12 of the supporting frame, and to the winding roll 18.

The winding roll comprises a shaft 20 operating within the sleeve 94. The opposite ends of the shaft are provided with pulleys 95 which are connected to the pulleys 96 on the motor shaft by means of the endless belts 97. The opposite ends of the sleeve 94 are formed with drums 98 and the portion of the shaft 20 extending through the drums are provided with a plurality of radially extending shanks 99 which slidably receive the sleeves 100 of the shoes 101. The outer surfaces of the shoes are maintained in pressed engagement with the inner periphery of the drums by the coil springs 102 to effect a friction drive for the winding roll.

The friction drive is necessary for the reason that the paper would tend to wind more rapidly around the sleeve 94 as the roll becomes larger thereby forcing the web of paper to pass more rapidly through the waxing vat 16 and cooling unit 17. The roller 72 will cause the paper to travel at a constant speed and rotation of the winding roll will keep the portion of the paper between the roller 72 and the winding roll tautly stretched over the idler roller 92, and as the quantity of paper on the winding roll becomes greater, the springs 102 will permit slippage between the drive shaft 20 and the roll of waxed paper.

The operation of the device is as follows: The paper is rolled from the supply roll 15 and threaded over the idler roller 32, under the adjustable idler rollers 34, between the rollers 41 and 52, under the cooling idler roller 54, and over the plate 64 below the hood 81 of the blower. From the plate 64 the paper passes over the drive roller 72 and under the idler roller 92 where it is connected to the winding roll 18. The motor 78 will drive the winding roll to wind the paper evenly and smoothly thereon. The motor will also drive the pump 66 to effect a continual flow of cooling solution through the roller 54 and tank 62, and the endless belts 76 will drive the vacuum cup roller 72 to feed the

paper through the various units at a constant speed. As hereinbefore described the idler roller 34 may be adjusted to cause the paper to pass a requisite distance below the surface of the waxing solution thereby causing the same to remain within the wax for a desired period of time in a manner to control the thickness of the layer of wax applied to the paper. The rubber roller 47 may be adjusted relative to the metal roller 52 to press the surplus wax from the paper, and passage of the waxed paper under the roller 54 will permit the cooling solution therein to harden the wax on the upper surface of the paper. The lower periphery of the cooling roller 54 is disposed slightly below the upper surface of the plate 64 in a manner to aid in holding the paper in pressed relation to the plate. The current of air generated by the blower 80 will be directed against the upper surface of the paper as it traverses the chilled plate 84 to dry and harden the wax thereon and to hold the paper in appressed relation with the plate.

The inclined position of the receptacle 62 assures contact of the cooling solution therein with the bottom surface of the plate 64 at all times. The pump 66 is adapted to force the cooling solution continuously through the receptacle 62; however, if the pump should fail to supply a quantity of the solution necessary to maintain the receptacle in a filled condition, the surface of the liquid within the tank would be lowered slightly and then only at the elevated end 68. The paper will pass from the plate 64 onto the roller 12 in a substantially dried state and the friction drive hereinbefore described for the winding roll will assure the smooth even winding of the same about the said roll.

It is to be understood that the form of my invention, herewith shown and described, is to be taken as a preferred example of the same, and that various changes in the size, shape and arrangement of parts may be resorted to without departing from the spirit of my invention, or scope of the appended claims.

Having thus described my invention, I claim:

1. A machine for waxing paper of the type including a receptacle for heated wax and means for guiding the paper through the receptacle, a tank for cooling liquid having an inclined essentially elongated chilled flat top surface over which the bottom side of the waxed paper is drawn, a chilled roller disposed between the wax receptacle and the cooling unit and with the periphery

thereof in intimate contact with the upper surface of the said paper for hardening the wax on the mentioned surface before the same contacts the tank, and means to direct a blast of air 5 against the hardened wax on the top surface of the paper to hold the same pressed against the chilled top surface of the tank.

2. In a combination with machine for waxing paper of the type including a receptacle for heated wax and means for guiding the paper through the receptacle, a cooling unit comprising a tank having an inclined essentially elongated chilled flat top surface over which the bottom side of the waxed paper is drawn, means to direct a blast of air against the paper in a manner to hold the same in appressed relation with the chilled surface of the cooling unit, said means including a hood having a discharge opening of substantially the same size as the top surface of the tank and the periphery of the hood being arranged in proximity to the top surface of the paper, and a chilled roller disposed between the wax receptacle and the cooling unit and with the periphery thereof in intimate contact with the upper surface of the said paper for hardening the wax on the top surface of the paper before the same is subjected to the blast of air from the said blower.

3. In a machine having means to coat a web of paper with wax, the improvement comprising an essentially elongated cooling tank inclined from the horizontal and including a chilled flat top surface adapted to have an intimate contact with one side of the waxed paper, a roller disposed 30 at the end of the cooling tank remote from the waxing means, the periphery of the roller being provided with suction cups adapted to grip the paper and to pull the same across the chilled surface of the tank, means to direct a blast of air against the paper in a manner to hold the same in pressed relation with the chilled surface of the cooling unit, said means including a hood 35 having a discharge opening of substantially the same size as the surface of the tank and the periphery of the hood being arranged in proximity to the top surface of the paper, and a chilled roller disposed between the wax receptacle and the cooling unit and with the periphery thereof in intimate contact with the upper surface 40 of the said paper for hardening the wax on the top surface of the paper before the same is subjected to the blast of air from the said blower.

JOHN BENNETT.
